UNITED STATES PATENT OFFICE

HENRY HENEL, OF KANSAS CITY, MISSOURI.

EGG-CASE.

1,236,561.

Specification of Letters Patent. Patented Aug. 14, 1917.

Application filed February 24, 1914. Serial No. 820,444.

To all whom it may concern:

Be it known that I, HENRY HENEL, a citizen of the United States, residing at Kansas City, in the county of Jackson and State 5 of Missouri, have invented certain new and useful Improvements in Egg-Cases; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to egg cases, and more particularly to a device for containing eggs in spaced relation, so that they may be shipped or carried without danger of breaking.

20 In accomplishing this object, I have provided improved details of structure herein-after described and illustrated in the accompanying drawings, wherein:

Figure I is a perspective view of an egg case constructed according to my invention; some of the compartments being empty to illustrate the construction of the partitions.

Fig. II is an elevation of the case; a part of the side being broken away to illustrate 30 the interior construction and use.

Fig. III is a detail perspective of a portion of a top or bottom spacer.

Referring more in detail to the parts:

1 designates a box or crate, which preferably comprises a body portion and lid of corrugated strawboard, or the like, the body having wooden ends 2 and the cover being provided with end ears 3, which overlie the ends of the body when the box is closed, and may be nailed thereto in order to hold the cover securely in place.

In the bottom of the box is a spacer 5 comprising a base 6 of cardboard or the like, and rails 7; the latter being also preferably 45 composed of stiff cardboard and crossed to form compartments.

In the preferred construction the rails 7 are permanently connected with the base 6, so that the parts may be installed and removed as a single unit. The base 6 has 50 apertures 8 therein through which the end

of an egg may be projected; the material of the base being slit from the aperture to render the base adjustable for different sizes of eggs.

Supported on the base 6 is a divider 11 comprising crossed strips of strawboard or the like, the ends of which project beyond the members which they cross, in order to space the latter from the sides and ends of the box, and supported on the top of the divider is a spacer 13 corresponding in size and construction with the bottom spacer 5 heretofore described.

In using a case of this kind, the bottom 65 spacer is first installed in the box and the divider then inserted and supported on the bottom spacer. The eggs to be shipped are then packed, one in each of the compartments and with their ends seated in the 70 apertures 8 in the bottom spacer.

When the crate is full of eggs, the top spacer is seated on the tops of the eggs, which project above the top of the divider so that the ends of the eggs project through 75 the apertures in the upper spacer; the apertures being enlarged, if necessary, by the eggs being projected into the apertures when the spacer is forced downwardly thereagainst, so that the eggs of different size 80 may be placed in the crate and all held firmly in place.

After the top spacer has been located, the cover of the box is closed and the cover ears nailed to the wooden ends of the body to 85 hold the parts firmly and securely in place.

With the eggs packed as described, each egg is held firmly in its own compartment and out of contact with the box, and with the members of the divider; the support 90 being only at the ends which project through and seat in the apertures in the top and bottom spacers.

It is apparent that being supported in this manner, the eggs cannot easily be broken 95 and may be shipped safely.

Having thus described my invention, what I claim as new therein, and desire to secure by Letters-Patent, is:

In an egg container, the combination of a 100 pair of spacers and a dividing member removably mounted between the spacers, said

spacers comprising base members having apertures therein in paired relation and in perpendicular alinement, and rails secured to the outer faces of the base members in crossed relation to form compartments about the apertures and to space the bases from the container, and said dividing member comprising crossed strips forming individ-

ual compartments about the apertures between the spacers.

In testimony whereof I affix my signature in presence of two witnesses.

HENRY HENEL.

Witnesses:

ARTHUR W. CAPS,
L. E. COATS.
